DESIGN FOR A COLLAPSIBLE COT OR SIMILAR ARTICLE

Tibor Schanzer, New York, N. Y.

Application September 11, 1944, Serial No. 115,263

Term of patent 14 years

(Cl. D5—4)

To all whom it may concern:

Be it known that I, Tibor Schanzer, a subject of Hungary, residing in New York city, county of New York, and State of New York, have invented a new, original, and ornamental Design for a Collapsible Cot or Similar Article, of which the following is a specification, reference being had to the accompanying drawings, forming part thereof, wherein,

I claim:

The ornamental design for a collapsible cot or similar article, substantially as shown.

TIBOR SCHANZER.
